UNITED STATES PATENT OFFICE.

GEORGE M. RHOADES, OF ASHTON, SOUTH DAKOTA.

SNOW-FENCE.

1,165,906.

Specification of Letters Patent. Patented Dec. 28, 1915.

Application filed June 7, 1915. Serial No. 32,789.

To all whom it may concern:

Be it known that I, GEORGE M. RHOADES, a citizen of the United States, residing at Ashton, in the county of Spink, State of 5 South Dakota, have invented certain new and useful Improvements in Snow-Fences; and I do hereby declare the following to be a full, clear, and exact description of the invention, such as will enable others skilled 10 in the art to which it appertains to make and use the same.

This invention relates to new and useful improvements in fences or barriers and is particularly directed to the provision of 15 such a device for use to prevent the drifting of snow, such devices being in use along railroads particularly in mountainous countries to prevent the drifting of snow over the tracks.

20 It is desirable to provide such devices which are of a knock-down nature, so that they may be readily transported from place to place and set up, as the necessity therefor arises, and it is the object of the present 25 invention to provide such a fence or barrier which is of a knock-down nature and which may be very readily set up in operative position and may be collapsed to occupy comparatively a very small space.

30 It is further an object to provide such a structure wherein the inclination thereof with respect to the ground may be adjusted readily to adapt it for use under various 35 conditions of service.

35 With the above and other objects and advantages in view, the invention resides more particularly in the novel combination, formation and arrangement of parts as more fully described hereinafter and pointed out 40 in the appended claim.

Reference is had to the accompanying drawings, wherein similar characters of reference designate corresponding parts throughout the several views, and in 45 which:—

Figure 1 is a perspective view of a snow fence structure constructed in accordance with the present invention; Fig. 2 is a front elevation of the improved fence structure; 50 Fig. 3 is an end edge view thereof, showing an adjusted position of the fence in dotted lines; Fig. 4 is a detail sectional view on the line 4—4 of Fig. 2; Fig. 5 is a perspective view of the upper portion of one of the posts

of the fence; and Fig. 6 is a perspective view of the panel structure of the fence.

Referring now more particularly to the accompanying drawings, the improved fence structure is shown as comprising a pair of end posts 5 which are preferably formed of 60 strips of sheet metal and which have their side edge portions bent backwardly upon their major portions as at 6 to form channels for receiving the ends of the panel members of the fence. A base is provided 65 for each of these posts and comprises a strip 7 of sheet metal bent longitudinally through its center and having its side portions bent outwardly to provide base flanges 8 through which are passed spikes 9 securing the base 70 to the ground. The lower end of each post 5 is pivoted at 10 to one end portion of a base, and pivoted to the upper end of each post is a brace 11 which is adapted to be adjustably connected to the base through the 75 medium of a bolt 12 passed through the brace and selectively passed through one of a series of openings 13 in the other end portion of the base. Thus the post may be adjustably held at any desired inclination to 80 the vertical to adapt the fence for use under different conditions of service.

The panel portion of the fence comprises a plurality of metal strips 14 which have their ends laterally directed at 15 to engage 85 in the channels formed by the sides 6 of the posts whereby they are held. These strips are connected together at their end portions by chain sections 16, to provide a flexible body portion. To provide a readily adjust- 90 able means for holding the panel body of the fence at any desired elevation, chain sections 17 are secured to the ends of the top strip 14 and are trained about pulleys 18 carried by the top portions of the post and 95 have certain of their links selectively engaged with hooks 19 carried by the brace members 11.

A very simple structure has thus been provided, which is fully adjustable to meet 100 various conditions of service and which may be readily disassembled and collapsed to occupy comparatively small space when not in use. In collapsing the end post structures the bolts 12 are removed and the braces 105 are then swung to lie along the posts and the posts are then swung to lie along the base members.

What is claimed is:—

A fence structure of the class described comprising a pair of base members, posts pivoted to adjacent end portions of the base members, braces pivoted to the posts and adjustably and detachably connected to the base members, holding channel portions formed on said posts, a plurality of flexibly connected panel strips having their end por-

tions slidably engaged in said channels and 10 means for adjustably holding said panel strips.

In testimony whereof, I affix my signature, in the presence of two witnesses.

GEORGE M. RHOADES.
